PISTON

James W. Brown, Oakland, Calif.

Application September 7, 1948, Serial No. 48,003

7 Claims. (Cl. 309—14)

1

This invention relates to a piston construction of the type used in reciprocating engines of the internal combustion class. It is conventional practice to allow for piston expansion in such engines by grinding the pistons to substantially smaller size than the bore of the cylinders which they are to fit, and then to employ compression rings to maintain a substantially gas-tight seal between each piston and its cylinder.

In the case of what are called "cam-ground" pistons, the piston is oval in shape having its major dimensions along a line at a right angle to the center of the axis of the wrist pin so that its fit within the cylinder is closest opposite the ends of said line and the tendency of the piston to rock on the axis of the wrist pin and cock the sharp edges of the compression rings into engagement with the cylinder walls is minimized. However, it is necessary even in such constructions to allow a minimum of 0.0005 inch clearance between the cylinder and the piston at the places just described and to allow for expansion of the piston with respect to its cylinder by allowing greater clearance between these places, so that as the piston expands it may be deformed from its original oval shape to a more nearly round shape.

In the case of "round-ground" pistons which are truly round in shape, much larger minimum clearances between the pistons and cylinders must be allowed at all points in order to permit expansion of each piston relative to its cylinder, and the tendency of the piston to rock on the axis of the wrist pin and cock the sharp edges of the compression rings into engagement with the cylinder walls is even greater than in the case of "cam-ground" pistons.

In either case, the amount of such cocking is sufficient to produce greater wear of the cylinder walls in the areas generally opposite the ends of a line drawn at a right angle to the center of the axis of the wrist pin, so that each cylinder wears unequally and compression is gradually decreased.

It is the principal object of the present invention to make possible a substantially closer fitting of the piston structures within the cylinders of internal combustion engines, without risk of seizure occurring by reason of expansion of the pistons relative to their cylinders. By thus decreasing the clearance between piston and cylinder, the cocking tendency referred to above is decreased to the point of substantial elimination, and the resulting wear of the cylinder walls in the areas mentioned is not substantially greater

2

than in any other area adjacent the piston, even where oil rings, or even light compression rings are used; although compression rings of the usual type are unnecessary with the piston of the present invention.

A further and important object of the invention is to make possible a closer fit of cylinder and piston in the area of the piston lying generally above the axis of the wrist pin, thereby still further decreasing the cocking tendency previously mentioned.

A still further and very important object of the invention is to provide a piston construction which will have substantially as close a fit within the cylinder when cold as it has at operating temperatures, thereby greatly reducing the cylinder wear incident to cold starting; which wear is very great in conventional constructions in which clearances of the order previously mentioned are allowed for the purpose of permitting expansion of the pistons relative to the cylinders.

Figure 1 is a vertical section through a piston construction embodying the invention showing the inner body of the piston as when expanded by heat;

Figure 2 is a similar view illustrating the contracted state of the inner body of the piston when cool;

Figure 3 is a view similar to Figure 2 showing a modification in structure; and

Figure 4 is a modification of the invention showing a piston in vertical section in which an accessory oil ring is employed.

In the preferred embodiments of the invention the piston structure consists essentially of three principal parts. The outer body, or sleeve 10, preferably of cast iron, is formed with a circumferential internal groove 11. Inside the upper portion of sleeve 10 there is a thin flexible steel ring or band 12 brazed or otherwise secured around its upper edge to the inner margin of the sleeve 10, as at 13, with its lower edge at about the center of groove 11. Internally of these there is the inner piston body and head 14 which in the embodiment illustrated is equal in vertical dimension to the outer sleeve 10. The inner body 14 is an aluminum alloy pressure die casting which is preferably cast into the sleeve 10 and ring 12 to complete the piston. The aluminum alloy is preferably cast into the sleeve and ring in molten state and in the process of casting some of the metal is forced into groove 11 and into intimate contact with both sides of the lower edge of the flexible steel ring 12, as at 15; and as it cools and shrinks it will form an air-tight seal

with the ring. However, the inner body may be machined to the same dimensions it would have if so cast, and an air-tight seal with the ring 12 effected by any desired means. The annular lug 16 produced by flow of the metal into groove 11 effectively locks the cast iron sleeve 10 against vertical movement with respect to the aluminum piston body 14. In the construction of Figures 1 and 2, as well as in the modifications of Figures 3 and 4, to be referred to, the aluminum alloy cast in molten state will contact the inner surfaces of sleeve 10 and ring 12, as illustrated by Figure 1. As the casting cools and contracts, it will shrink away from sleeve 10 as illustrated by Figure 2 and the elements of the assembly will assume substantially the relation there shown, the lower end of the flexible steel ring 12 being drawn away from sleeve 10 with lug 16 while preserving an air-tight seal at the joint.

In the modified construction of Figure 3, the connections of the steel ring 12a are shown as reversed. To accomplish this the circumferential groove, here designated 14a, is formed adjacent the top of sleeve 10a and the ring 12a is secured at its lower edge to the sleeve at 13a and has its upper edges embedded in lug 16a in the same manner as in the first construction described.

The modification of Figure 4 differs from that of Figures 1 and 2 only in the provision of a ring groove 17 in the outer sleeve 10 designed to receive an oil ring 18. In this construction the cast iron sleeve 10 is thickened at the groove location to provide the required ring seat, as shown, forming an annular protuberance 19 on the inner surface of the sleeve. This serves as an additional lock between the aluminum inner piston 14 and the sleeve 10. After the aluminum piston is cast, as before described, circumferential oil drain apertures 20 preferably are provided as by drilling through the bottom of groove 17 and the skirt of piston 14 as shown.

As well known to the art, the head of a piston is subjected to the highest heat and will expand against the cylinder wall under conditions producing high heat and contract away under conditions of low heat and is, therefore, the most troublesome part of a piston. With the piston of the present invention, the head is poured into the cast iron sleeve in a molten state. As it cools it shrinks away from the sleeve which is in contact with the cylinder wall. Under operating conditions the aluminum piston and head will never become as hot as when it was formed and so can never expand to a degree where it would put pressure on the cast iron sleeve and force it against the cylinder wall. The cast outer sleeve will, therefore, tend to run at an equal temperature to the cast iron cylinder wall and if any expansion or contraction takes place in the cylinder wall, it will be practically constant with that of the cast iron piston sleeve. Hence, when the cast sleeve of the piston herein disclosed is either lapped into a cylinder or ground to equivalent dimensions there will be a constant fit under operating conditions between the cylinder and piston. Furthermore, use of aluminum for the inner body and head of the piston will result in a considerable reduction in weight with a consequent gain in engine efficiency.

Utilizing pistons embodying the present invention it has been found possible to employ round ground piston constructions in which, in a one

cylinder, one and three quarter inch bore, air-cooled, four cycle engine, a clearance of only .0002 of an inch was maintained between the piston sleeves and the cylinder walls, and completely successful operation was demonstrated by an extended test.

It will be evident from the above disclosure that a simplified and highly efficient piston construction has been provided by this invention and that further modifications of the structures disclosed could be made without departure from the scope of the invention as defined in the claims.

What is claimed is:

1. In a piston for reciprocating engines, an outer cast iron sleeve formed with a circumferential groove in its inner surface, an integral aluminum body and head co-extensive with said sleeve and fitted within the sleeve with an integral circumferential lug projecting into said groove, and a continuous flexible steel band positioned between the sleeve and body adjacent the upper ends thereof and having its opposite edges sealed to the sleeve and body respectively.

2. In a piston for reciprocating engines, an outer cast iron sleeve, an inner aluminum head and body co-extensive with said sleeve fitted within the sleeve, interlocking elements between the sleeve and body for preventing relative movement longitudinally, and a continuous flexible steel band positioned between the sleeve and body and having its opposite edges sealed to the sleeve and body respectively.

3. In a piston for reciprocating engines, an outer cast iron sleeve, an inner aluminum head and body fitted within said sleeve, interlocking elements between the sleeve and body for preventing relative movement longitudinally, and a continuous flexible steel band positioned between the sleeve and body and having its opposite edges sealed to the sleeve and body respectively.

4. In a piston for reciprocating engines, an outer cylinder engaging sleeve, an inner body forming the piston head fitted within said sleeve and formed of an alloy having a higher coefficient of expansion than the sleeve, means on the sleeve and body for preventing relative longitudinal movement, and a continuous flexible metal band having its opposite edges in sealed union with the sleeve and inner body respectively.

5. In a piston for reciprocating engines, an outer cylinder engaging sleeve, an inner body of aluminum alloy, forming the piston head, cast within said sleeve, interlocking means between the sleeve and body for preventing relative longitudinal movement, and a continuous flexible metal seal uniting the sleeve and body.

6. In a piston for reciprocating engines, an outer cast iron sleeve formed with a circumferential groove in its inner surface, a second circumferential groove formed on the outer surface of the sleeve below the location of the internal groove and provided with oil drainage apertures in its base, an inner aluminum head and body fitted within said sleeve and formed with a projecting portion engaged in said internal groove, a flexible metal band positioned between the sleeve and body adjacent the upper ends thereof and having its upper edge sealed to the upper edge of the sleeve and its lower edge sealed to the body at the portion thereof projecting into the internal groove, and an oil ring seated in the external circumferential groove.

7. In a piston for reciprocating engines, an

outer cylinder-engaging sleeve, an inner body forming the piston head fitted within said sleeve and formed of an alloy having a higher coefficient of expansion than the sleeve, means on the sleeve and body for preventing relative longitudinal movement, and a relatively thin elongate metal band having its opposite edges in sealed union with the sleeve and inner body respectively.
